CLAIM

The ornamental design for a faucet body, as shown and described.

DESCRIPTION

FIG. 1 is a top, rear, right side perspective view of a faucet body showing my new design;

FIG. 2 is a top plan view thereof;

FIG. 3 is a bottom plan view thereof;

FIG. 4 is a left side elevational view thereof, the right side being the mirror image of the left side;

FIG. 5 is a front elevational view thereof;

FIG. 6 is a rear elevational view thereof; and

FIG. 7 is a top, rear, right side perspective view of a second embodiment thereof.

The broken line representation of holes in FIGS. 1 through 3 and 5 through 7 are for purposes of illustration only and form no part of the claimed design.

FIG. 1

FIG. 2

FIG. 7

FIG. 6
